UNITED STATES PATENT OFFICE.

ELVERTON M. HEMPHILL, OF ELMIRA, NEW YORK.

LUBRICATING-CUP.

1,355,668.

Specification of Letters Patent.

Patented Oct. 12, 1920.

Application filed December 19, 1919. Serial No. 345,986.

To all whom it may concern:

Be it known that I, ELVERTON M. HEMPHILL, a citizen of the United States, residing at Elmira, in the county of Chemung and State of New York, have invented certain new and useful Improvements in Lubricating-Cups, of which the following is a specification.

My invention relates to an improvement in lubricating cups, and the object is to provide a cup in which either oil or grease may be used, it consisting of a force feed for compressing the lubricant and insuring its feed, and a capillary device which also insures and facilitates a uniform feed of lubricant to the part to be lubricated.

In the accompanying drawings:

Figure 1 is a sectional view through one form of my cup;
20 Fig. 2 is a sectional view through a slightly modified form.

In the construction shown in Fig. 1, A is the cup having an external screw-thread 1; and 2, represents an internally-threaded cap adapted to screw on these threads. This cap has a hole 3 through the center, and through it the stem 4 of a threaded plunger 5 extends. The bottom 6 of the cup preferably slopes more or less to a central point where a hole is formed, and extending up through this hole is an upstanding tube 7 of suitable height, the bore of which leads down through a threaded nipple 8, which is adapted to screw down into the bearing to be lubricated.

A lateral hole or duct 9 is bored transversely through the upstanding tube at the very bottom of the cup, so that the cup has two outlets, one at the top, and the other 40 at the bottom of the upstanding tube.

A capillary device consists of a wicking 10 of absorbent material, and this is removably held in the tube 7 in any approved manner, preferably by means of a wire 11 having a loop 12 on one end, by which it is secured to the absorbent wicking 10, and a loop or handle 13 at the upper end. The wicking may be conveniently wound around the wire, and then the wire with the wicking inserted in the tube 7 with the free end of the wicking loose in the cup, so that it will by capillary attraction keep the wick well saturated with oil, and a constant yet

choked feed of lubricant as a result to the part to be lubricated.

The cup may be used for grease by removing the capillary device altogether, but when oil is used it prevents too free a flow of the oil, and at the same time regulates its feed so that it is more or less uniform at all times.

As the supply of oil or grease becomes exhausted, the handle 14 on the plunger-rod is turned to the right screwing the plunger in, thus creating pressure upon the upper surface of the oil or grease, in this way forcing it out into the bearing, and insuring or increasing the feed of oil or grease at any time desired.

In the construction shown in Fig. 2, the cap is in the form of a plug 15, which screws into an internal thread in the cup, and while a sufficient number of threads to the inch (say sixteen) will insure against the plug turning accidentally, the spiral spring is secured to the plug at its outer end, and bears at its inner end against the bottom of the cup. In that way by outward spring pressure against the plug, it absolutely prevents the latter from accidentally turning from the position in which it may be turned in the exercise of its function as a force feed plunger.

In the actual use of these cups, I have found them most effectual for the purpose for which they are designed, either as a force feed, grease, or dope cup, or an oil cup, for any part that requires constant lubrication, as for instance the various bearings in an automobile, for example the roller bearings in a steering-gear, although it is understood the invention is applicable to any bearing or part to be lubricated.

I claim:

1. A lubricating device including a cup having a screw threaded orifice in the bottom, a tube having an external thread which screws upwardly into the hole in the bottom of the cup and protrudes some distance into the cup, the end protruding into the cup having a lateral hole above and adjacent to the bottom of the cup, and a force feed device at the upper end of the cup whereby lubricant is forced out of the cup through the tube.

2. A lubricating device including a cup

having a screw threaded orifice in the bottom, a tube having an external thread which screws upwardly into the hole in the bottom of the cup and protrudes some distance 5 into the cup, the end protruding into the cup having a lateral hole above and adjacent to the bottom of the cup, a force feed device at the upper end of the cup whereby

lubricant is forced out of the cup through the tube, and a capillary device extending ¹⁰ from the cup into and approximately throughout the length of the tube for regulating the flow of lubricant out of the cup.

In testimony whereof I affix my signature.

ELVERTON M. HEMPHILL
